UNITED STATES PATENT OFFICE

2,582,912

TILTING MECHANISM FOR FOUNDRY
LADLES AND THE LIKEAnthus D. Oldham, Harvey, and Frank J. Sabla,
South Holland, Ill., assignors to Whiting Cor-
poration, Harvey, Ill., a corporation of Illinois

Application June 8, 1945, Serial No. 598,338

4 Claims. (Cl. 22—82)

1

The present invention relates generally to ladles. More particularly the invention relates to that type of ladle which is primarily designed for use in a foundry, serves as a medium or instrumentality for introducing molten metal into flasks and as its principal parts or components comprises: (1) a bail which is adapted to be attached to the hook of an overhead crane in order that the ladle may be moved or shifted back and forth between the source of molten metal and the flasks to be filled; (2) a pot which functions as a container for the molten metal, has a lining of refractory material, and is provided with outwardly extending trunnions on diametrically opposite portions of its side wall whereby it is pivotally connected to the lower ends of the legs of the bail so that it is capable of tilting back and forth between an upstanding charging position and an angularly disposed pouring or discharging position; and (3) pot tilting gearing which is mounted or disposed within a housing on one leg of the bail, has a hand wheel or other means associated with it for actuating purposes, and is operatively connected to the adjacent pot trunnion.

In connection with use of a foundry ladle of this type it is necessary periodically to reline the pot. Relining of the pot with refractory material entails heating of the lining for curing purposes and results in the ladle as a whole being out of use for a considerable period of time. In practice it has been found that heating of the new lining of refractory material while the pot tilting gearing is mounted in place on the bail is detrimental and in certain instances quite injurious to the gearing and the lubricant for the gearing.

One object of the invention is to provide a foundry ladle of the type under consideration which is an improvement upon, has certain advantages over, previously designed foundry ladles and is characterized by the fact that the housed gearing for tilting the pot is capable of being quickly and readily detached from the bail. As a result of the fact that the pot tilting gearing is detachably mounted with respect to the bail it may be removed during a pot relining operation so that it together with its lubricant is not subjected to deleterious heat and it is possible to use the gearing in connection with another ladle, the pot of which has already been relined.

Another object of the invention is to provide a foundry ladle of the last mentioned type and character in which the housing and gearing constituting the unit for tilting the pot with respect

2

to the bail are so designed and constructed that the unit not only is capable of being detached from the bail with facility but also is sealed against loss of the gearing lubricant when it is removed from the bail.

Another object of the invention is to provide a foundry ladle of the aforementioned type in which the gearing is so designed and arranged that it occupies but a small space and hence it is possible so to reduce the size of the housing that the pot tilting unit as a whole occupies a minimum amount of space.

Another object of the invention is to provide a foundry ladle of the type and character last mentioned in which the housing of the pot tilting unit has a removable cover plate on its outer side and certain parts of the gearing are mounted on the cover plate to the end that they are readily accessible for inspection, repair or replacement purposes upon removal of the cover plate.

A further object of the invention is to provide a foundry ladle of the type under consideration in which the housing of the pot tilting unit embodies on the top portion thereof a bifurcated bracket which is in straddled relation with the adjacent leg of the bail and serves as a torque arm for preventing rotative displacement of the housing relatively to the bail.

A still further object of the invention is to provide a foundry ladle which is generally of new and improved construction and is characterized by the fact that it is highly efficient and extremely durable.

Other objects of the invention and the various advantages and characteristics of the present foundry ladle will be apparent from a consideration of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views:

Figure 1 is a front elevation of a foundry ladle embodying the invention;

Figure 2 is a plan view illustrating in detail the arrangement and design of the bracket which is mounted on the top portion of the housing for the gearing and serves to hold the pot tilting unit against tilting or angular displacement with respect to the bail;

Figure 3 is an enlarged front elevation of the

housing and gearing constituting the unit for tilting the pot with respect to the bail back and forth between its upstanding charging position and its angularly disposed pouring or discharging position;

Figure 4 is an enlarged side view of the pot tilting unit, one of the parts thereof being shown in a fragmentary manner for purposes of illustration;

Figure 5 is a vertical transverse section taken on the line 5—5 of Figure 4 and illustrating in detail the construction, design and manner of mounting of the sleeve which serves operatively to connect the gearing to the adjacent pot trunnion and forms a seal for preventing leakage of the gearing lubricant from the housing when the pot tilting unit is removed from the bail; and

Figure 6 is a vertical longitudinal section taken on the line 6—6 of Figure 3 and showing in detail the arrangement and manner of mounting the gearing;

Figure 7 is a vertical transverse section taken on the line 7—7 of Figure 4 and illustrating the construction and arrangement of the automatic means for feeding the lubricant in the housing onto the gearing and bearings in response to drive or operation of the gearing;

Figure 8 is a perspective view of the pot tilting unit;

Figure 9 is a perspective view of the unit, the removable cover plate being shown in separated relation with respect to the housing proper; and

Figure 9a is a perspective of certain parts of the automatic lubricant feeding means.

The ladle which is shown in the drawings constitutes the preferred form or embodiment of the invention. It is designed or adapted for use in a foundry and serves to introduce molten metal into flasks. As its main or principal components the ladle comprises a bail 10, a pot 11 and a detachable pot tilting unit 12.

The bail 10 consists of an inverted V-shaped cross member 13 and a pair of depending legs 14 and 15 at the ends of the cross member. It is in the form of a rigid unit and is adapted to be attached to the hook of an overhead crane in order that the ladle may be moved or shifted by the crane back and forth between the source of molten metal and the flasks to be filled. The lower end of the leg 14 of the bail is provided with a fixed bearing 16, and the lower end of the other leg of the bail, i. e., the leg 15, is provided with a fixed bearing 17.

The pot 11 serves as a container for the molten metal and is disposed between the depending legs of the bail as shown in Figure 1. It has a lining of refractory material and embodies outwardly extending trunnions 18 and 19 on diametrically opposite portions of its side wall. The trunnion 18 is journaled in the bearing 16 on the lower end of the bail leg 14 and the trunnion 19 is of materially greater length than the trunnion 18 and extends through and is journaled in the bearing 17 on the lower end of the bail leg 15. The two trunnions permit the pot 11 to be tilted back and forth between an upstanding charging position and an angularly disposed pouring or discharging position as well understood in the art. The front portion of the upper margin of the pot is provided with a spout 20 for guiding the molten metal when the pot is tilted into its discharging position in connection with a pouring operation.

The pot tilting unit 12 is located outwards of the leg 15 of the bail and comprises a housing 21 and gearing 22. As hereinafter described more

in detail the various parts of the gearing 22 are disposed and mounted within the housing 21.

The housing 21 is preferably formed of cast metal and comprises a top wall 23, a front wall 24, a back wall 25, a bottom wall 26 and an inner side wall 27. Such walls are preferably formed integrally with one another and together with a main cover plate 28 define a compartment 29 for the various parts of the gearing 22. The compartment is adapted to be partially filled with oil or any other suitable lubricant in order to effect lubrication of the gearing. In addition to the walls 23, 24, 25, 26 and 27 the housing comprises a continuous flange 30. This flange is formed integrally with, and projects outwards from, the outer side margins of the top, bottom, back and bottom walls of the housing. The main cover plate 28 is shaped conformably to, and fits flatly against, the flange 30 and is removably secured in place by means of cap screws 31. The shanks of the latter extend through aligned screw threaded holes in the cover plate 28 and the flange 30. The top wall 23 of the housing is provided at one end thereof with an opening 23a through which the parts within the casing may be inspected. The inner side wall 27 and the main cover plate 28 are positioned in parallel relation and have in the lower portions thereof aligned circular holes 32 through which the outer end of the pot trunnion 19 extends. The holes 32 are the same in diameter but are, however, of materially greater diameter than said trunnion. When the pot tilting unit 12 is in connected or operative relation with the bail the housing 21 is held against tilting or rotative movement with respect to the bail by means of a bracket 33. The latter is bolted or otherwise removably secured to the portions of the top wall that defines the inspection opening 23a. It serves when in place to close said opening and embodies a laterally extending bifurcated extension 34 which is shaped to straddle the upper end or portion of the leg 15 of the bail. The outer ends of the bifurcations of the extension 34 are provided with aligned holes 35 for a bolt 36. This bolt serves releasably to hold the bifurcated extension 34 in connected relation with the upper end of the bail leg 15. When the bolt 36 is removed from the holes 35 the housing 21 and the gearing 22 constituting the pot tilting unit 12 may be shifted laterally away from the bail. The central portions of the bifurcations of the extensions 34 are provided with set screws 37 and these are adapted to engage the sides of the bail leg 15 and serve angularly to adjust the housing 21 with respect to the bail. When it is desired to remove the pot tilting unit the set screws 37 are first loosened. Thereafter the bolt 36 is withdrawn from the holes 35 so as to free the bifurcated extension of the bracket 33 from the upper end of the bail leg 15 and thus permit the unit to be shifted laterally away from the bail. When it is desired to mount the unit 12 with respect to the bail the housing 21 is manipulated so as to align the holes 32 in the inner side wall 27 and the cover plate 28 of the housing with the trunnion 19 and at the same time align the bifurcated extension 32 with the upper end of the bail leg 15. Thereafter the unit is shifted laterally towards the bail in order to cause the outer end of the trunnion 19 to enter the housing via the innermost hole 32 and the upper end of the bail leg 15 to be disposed within the bifurcated extension 34 of the bracket 33. After shift of the unit into place the bolt 36 is inserted through the holes 35 and the set screws

37 are tightened. The bifurcations of the extensions 34 are spaced apart a sufficient distance to accommodate bail legs which vary in width within a given range, and the set screws serve fixedly to connect the extensions to the adjacent bail leg when the unit is in its operative position.

The gearing 22 has associated with it a hand wheel 38 for actuating purposes and comprises a pair of bevel gears 39 and 40, a worm 41, a worm gear 42 and a sleeve 43. The hand wheel 38 is disposed outwards of, and in parallel relation with the main cover plate 28 and has the hub thereof fixedly connected to the outer end of a horizontal shaft 44 which extends at right angles to the housing 21. The central portion of the shaft 44 is journaled in antifriction bearings 45 within a tubular member 46 and the inner end of the shaft extends through a hole 28a in the main cover plate 28 of the housing. The inner end of the tubular member 46 has an outwardly extending flange 47 which fits flatly against the outer face of the portion of the main cover plate 28 that defines the hole 28a, and is removably secured to the main cover plate by cap screws 48. The bevel gear 39 is keyed or otherwise fixedly connected to the inner end of the shaft 44 and is disposed in the upper portion of the compartment 29 and adjacent the upper portion of the main cover plate 28. When the cover plate is removed from the housing 21 by releasing or withdrawing the cap screws 31, the assembly consisting of the hand wheel 38, the shaft 44, the bearings 45, the tubular member 46 and the bevel gear 39 is likewise removed from the housing. The bevel gear 40 meshes with and is driven by the bevel gear 39 and is fixedly connected to one end of a shaft 49. Such shaft extends lengthwise across the upper portion of the compartment 29 and has its ends journaled in a pair of antifriction bearings 50 which are disposed within, and connected to, a pair of cupshaped caps 51. As best shown in Figure 6, the caps extend through aligned circular holes 52 in the front and rear walls 24 and 25 of the housing and are removably secured in place by cap screws 53 which extend through holes in outwardly extending flanges 51a on the caps and into screw threaded sockets in the portions of the front and rear walls that define the holes 52. The bearings 50 and the caps 51 serve when in place to hold the shaft 49 against axial displacement with respect to the housing 21. The bevel gear 39 is located adjacent the central portion of the shaft 49 and the teeth of the mating bevel gear 40 faces in the direction of said central portion of the shaft. As the result of this particular arrangement of the two bevel gears the gearing 22 is so compact that it is possible to make the housing 21 extremely small to the end that the pot tilting unit 12 occupies but a small amount of space. The worm 41 is formed integrally with the shaft 49 and meshes with, and serves to drive, the worm gear 42. The latter is disposed in the lower portion of the compartment 29, as shown in Figure 6, extends around the central portion of the sleeve 43, and is fixedly secured to the sleeve by way of a key 54 which fits within a keyway 55 in the hub of the worm gear and a keyway 56 in the central portion of the sleeve 43. The sleeve is disposed beneath, extends at right angles to, the shaft 49 and has its ends journaled in a pair of flanged bearings 57. The latter fit within the holes 32 in the lower portions of the inner side wall 27 and the main cover plate 28 of the housing and are arranged so that the

flanges thereof are disposed interiorly of the compartment 29. The bearing flanges abut against the ends of the hub of the worm gear 42, as shown in Figure 6, and serve to hold the assembly of worm gear and sleeve against axial displacement with respect to the housing 21. The inner periphery of the sleeve 43 is shaped slidably to receive the outer end of the pot trunnion 19 and has a longitudinal key-way 58 for a key 59. The latter fits within a longitudinal key-way 60 in the outer end of the pot trunnion 19 and serves to connect the trunnion for drive by the sleeve when the pot tilting unit 12 is in its operative position, i. e., is in connected relation with the bail 10 of the ladle. The end of the key 59 that is nearer the leg 15 of the ladle bail 10 is provided with an enlarged outwardly and laterally extending head 59a which fits within a notch 43a in the adjacent end of the sleeve 43 and is of such length that it serves to prevent the housing 21 from being positioned too close to the bail leg 15. A plate-like retainer member 61 together with a plurality of cap screws 62 serves releasably to prevent outward movement of the pot tilting unit 12 with respect to the trunnion 19. This retainer member is disposed adjacent the outer end of the sleeve 43, i. e., the end of the sleeve that is directly opposite the main cover plate 28 of the housing 21 and has holes 63 in its central portion for the shanks of the cap screws 62. The margin of the retainer member 61 embodies a plurality of equidistantly spaced outwardly extending lugs 64 and these fit within notches 65 in the adjacent end of the sleeve 43. The inner ends of the shanks of the cap screws 62 fit within screw threaded sockets 66 in the outer end of the pot trunnion 19. When the retainer member 61 is connected to the trunnion 19 by way of the cap screwed 62 it prevents the sleeve from being displaced axially outwards with respect to the trunnion. The outer end of the hole 32 in the lower portion of the main cover plate 28 is normally closed or covered by a plate 67 which is removably secured in place by cap screws 68. The shanks of the screws 68 extend through registering screw threaded holes in the marginal portion of the plate 67 and the hole defining portion of the main cover plate 28. When it is desired to remove the plate 67 in order to provide access to the retainer member 61 it is only necessary to remove the cap screws 68. When the unit 12 is in attached or connected relation with the bail 10 of the ladle turning of the hand wheel 38 causes the gearing 22 so to revolve as to cause tilting of the pot 11 in one direction. Reverse turning or rotation of the hand wheel 38 effects reverse drive of the gearing and thus causes the pot to tilt in the opposite direction. In view of the fact that the gearing 22 includes the worm 41 and the worm gear 42 the gearing is irreversible and hence the pot can be tilted only by turning the hand wheel.

In addition to the parts heretofore described the pot tilting unit 12 comprises automatic means for feeding the lubricant from the bottom portion of the compartment 29 onto the gearing 22 in response to drive of the gearing by rotation of the hand wheel 38. Such automatic lubricant feeding means embodies a pump 69 which is located in the lower portion of the compartment 29 and is disposed beneath the end of the shaft 49 that carries the bevel gear 40. The pump is of the reciprocating plunger type and comprises a vertically extending cylindrical casing 70 and a vertically slidable plunger (not shown) in the

7
casing 70. The pump casing 70 embodies in the lower end thereof a check valve equipped inlet port (not shown) and has a check valve equipped outlet port (also not shown) in its upper end. A C-shaped bracket 71 serves to connect the pump casing 70 to the inner face of the removable cover plate 28. This bracket has the lower leg thereof suitably connected to the upper end of the pump casing. The central or intermediate part of the bracket is flat and fits against the inner face of the cover plate 28. Two cap screws 72 extend through holes in the cover plate into screw threaded sockets in the central part of the bracket and serve removably to secure the bracket to the cover plate. The pump plunger is provided with an upwardly extending stem 73 and this extends through, and is slidably mounted in, a pair of vertically aligned holes 74 in the upper and lower legs of the C-shaped bracket 71, and has a reduced central portion 75. A coil variety compression spring 76 surrounds the upper end of the stem 73 of the plunger, is interposed between the upper leg of the C-shaped bracket 71 and a collar 77 on the stem, and serves to urge the pump plunger downwards. One end of a lubricant feed pipe 78 is connected to the check valve equipped outlet port of the pump casing 70 and the other end of the pipe is arranged in overhanging relation with the bevel gear 40 and the worm 41 and has downwardly facing orifices for jetting lubricant onto said bevel gear and worm. When the plunger of the pump 69 is reciprocated lubricant is drawn into the pump casing 70 via the aforementioned check valve equipped inlet port and is forced under pressure into the feed pipe 78 via the check valve equipped outlet port in the upper end of the pump casing. The pumped lubricant, after flowing through the pipe, is jetted in stream form downwards onto the bevel gear 40 and the worm 41 in order to lubricate the latter. The pipe 78 is clamped against the inner face of the main cover plate 28 by bolt equipped clips 79. By reason of the fact that the pump 69 and the feed pipe 78 are attached to the cover plate 28 they are removable with the cover plate when the latter is disconnected or released from the housing 21 of the pot tilting unit 12. The plunger of the pump is reciprocated in response to drive of the gearing 22 by means of a star wheel 80 and a bell crank 81. The star wheel 80 is mounted on the shaft 49 and is formed integrally with the outer end of the hub of the bevel gear 40. The bell crank 81 is located in the compartment 29 adjacent the back wall 25 of the housing 21 and comprises a substantially vertical arm 82 and a substantially horizontal arm 83 at the lower end of the arm 82. It is pivotally connected to the housing back wall 25 by way of a pivot bolt 84 which extends through the connected ends of the arms 82 and 83 and fits within a screw threaded socket in the housing back wall 25. The upper end of the substantially vertical arm 82 of the bell crank is provided with a roller 85 which is arranged successively to engage the teeth of the star wheel 80. The outer or distal end of the horizontal arm 83 of the bell crank 82 is provided with a fork 86. This is arranged in straddled relation with the reduced central portion 75 of the stem 73 of the pump plunger. When the star wheel 80 is rotated in response to drive of the gearing 22 by turning of the hand wheel 38 it operates to rock the bell crank 81 back and forth and the bell crank, in turn, effects reciprocation of the plunger of the pump 69. The compression spring 76 is indirectly applied to the bell

crank in such manner that it operates to hold the roller 85 in contacting relation with the star wheel 80. The fork 86 on the outer or distal end of the bell crank arm 82 permits the pump 69 to become disconnected from the bell crank when the main cover plate 28 is removed from the housing 21.

It is contemplated that the pot tilting unit 12 will be detached from the bail 10 in connection with relining of the pot 11. When it is desired to detach the unit the plate 67 is first removed by releasing or withdrawing the cap screws 68. After removal of the plate 67 the cap screws 62 are removed so as to free the plate-like retainer member 61 from the pot trunnion 19. After freeing of the member 61 the bolt 36 is removed from the bifurcated extension 34 on the bracket 33 and the set screws 37 are loosened. Thereafter the entire unit is shifted laterally away from the bail 10. When the unit 12 is disconnected from the bail it may be used to form part of another ladle, the pot of which has a new or usable lining of refractory material. When it is desired again to attach the unit 12 to the bail 10 the housing 21 for the gearing 22 is manipulated so as to bring the sleeve 43 into alignment with the trunnion 19 and the bifurcated extension 34 into alignment with the upper end of the bail leg 15. Thereafter the unit is shifted laterally towards the bail until the outer end of the trunnion 19 is disposed fully within the sleeve and is connected to the latter by way of the key 59. After shifting of the unit the bolt 36 is inserted through the holes 35 and the plate-type retainer member 61 is applied to the outer end of the trunnion by the cap screws 62. After tightening of the cap screws 62 the plate 67 is connected in place by the cap screws 68. By reason of the fact that the sleeve 43 has its ends journalled in the flanged bushings 57 the housing 21 is sealed against loss of lubricant when the unit is in its detached position. In the event it is necessary to inspect, repair or replace the gearing 22 or the pump 69 the main cover plate 28 is removed from the housing 21 by withdrawing the cap screws 31.

55 The herein described foundry ladle effectively and efficiently fulfills its intended purpose and is characterized by durability and simplicity of design and construction. It is further characterized by the fact that the pot tilting unit 12 is capable of being quickly and readily detached from the bail, and the sleeve 43 constituting part of the gearing serves to seal the housing against loss of lubricant when the unit is disconnected from the bail.

56 Whereas the tilting unit or mechanism has been described as being adapted primarily for use in connection with a foundry ladle it is to be understood that it has other capabilities of use. It is also to be understood that the invention is not to be restricted to the details set forth since these may be modified within the scope of the appended claims without departing from the spirit and scope of the invention.

65 Having thus described the invention what we claim as new and desire to secure by Letters Patent is:

70 1. A detachable unit designed for use in tilting a foundry ladle of the type that comprises a bail with a depending bearing equipped leg and a tiltable pot with a trunnion journalled in the bearing and having the outer end thereof projecting beyond the bearing, said unit being adapted when in use to be positioned outwards 75 of the bearing equipped leg of the bail, and

embodying a housing provided with means for detachably connecting it to the bail, having a circular over-sized hole in the inner side wall thereof for reception of the projecting outer end of the trunnion, provided with a bearing in the hole and an internally disposed bearing in axial alignment and spaced relation with the last mentioned bearing, and adapted to retain lubricant, and gearing mounted in the housing and including a rotatable sleeve-like element having the ends thereof journaled in the last two mentioned bearings and its interior out of communication with the housing interior and shaped slidably to receive said projecting outer end of the trunnion, adapted in connection with attachment of the housing to the bail to slide onto the projecting outer end of the trunnion and in connection with detachment of the housing from said bail to slide out of engagement with said projecting outer end of the trunnion, provided with a releasable trunnion driving connection in the form of a plate type member having a bolt for connecting it to the outer end of the trunnion and interlocking means between it and one end of the sleeve, and adapted to seal the housing against leakage of the lubricant through the hole when the housing is detached from the bail.

2. A detachable unit designed for use in tilting a foundry ladle of the type that comprises a bail with a depending bearing equipped leg and a tiltable pot with a trunnion journaled in the bearing and having its outer end projecting beyond the bearing, said unit when in use being adapted to be positioned adjacent the bearing equipped leg of the bail, and embodying a housing having means for detachably connecting it to the bail, provided with an over-sized hole in one of the walls thereof for reception of the projecting outer end of the trunnion, and adapted to retain a lubricant, and gearing mounted in the housing and including a rotatable sleeve fitting within said hole, having the interior thereof out of communication with the interior of the housing, and shaped slidably to receive said projecting outer end of the trunnion, adapted in connection with attachment of the housing to the bail to slide onto the projecting outer end of the trunnion and in connection with detachment of the housing from said bail to slide out of engagement with said projecting outer end of the trunnion, provided with a releasable trunnion driving connection in the form of a plate type member having a bolt for connecting it to the outer end of the trunnion and interlocking means between it and the one end of the sleeve, and adapted to seal the housing against leakage of the lubricant through the hole when the housing is detached from the bail.

3. A detachable unit designed for use in tilting a foundry ladle of the type that comprises a bail with a depending bearing equipped leg and a tiltable pot with a trunnion journaled in the bearing and having its outer end projecting beyond the bearing, said unit being adapted when in use to be positioned outwards of the bearing equipped leg of the bail, and embodying a housing provided with means for detachably connecting it to the bail, having inner and outer side walls with aligned bearing equipped holes therein, and adapted to retain a lubricant, and gearing mounted in the housing and including a rotatable sleeve having the ends

thereof journaled in the bearing equipped holes and its interior out of communication with the housing interior and shaped slidably to receive the projecting end of the trunnion, adapted in connection with attachment of the housing to the bail to slide onto the projecting outer end of the trunnion and in connection with detachment of the housing from said bail to slide out of engagement with said projecting outer end of the trunnion, provided with a releasable trunnion driving connection in the form of a plate type member having a bolt for connecting it to the outer end of the trunnion and interlocking means between it and one end of the sleeve, and adapted to seal the housing against leakage of the lubricant through the bearing equipped holes when the housing is detached from the bail.

4. A detachable unit designed for use in tilting a foundry ladle of the type that comprises a bail with a depending bearing equipped leg and a tiltable pot with a trunnion journaled in the bearing and having its outer end projecting beyond the bearing, said unit being adapted when in use to be positioned outwards of the bearing equipped leg of the bail, and embodying a housing provided with means for detachably connecting it to the bail, having a fixed inner side wall and a removable cover plate in laterally spaced relation with the inner side wall, provided with aligned bearing equipped holes in said inner side wall and cover plate, and adapted to retain a lubricant, gearing mounted in the housing and including a rotatable sleeve having the ends thereof journaled in the bearing equipped holes and the interior out of communication with the interior of the housing and shaped slidably to receive the projecting outer end of the trunnion, adapted in connection with attachment of the housing to the bail to slide onto the projecting outer end of the trunnion and in connection with detachment of the housing from said bail to slide out of engagement with said projecting end of the trunnion, provided with a releasable trunnion driving connection accessible via the bearing equipped hole in the cover plate and in the form of a plate-type member having a bolt for connecting it to the outer end of the trunnion and interlocking means between it and the adjacent end of the sleeve, and adapted to seal the housing against leakage of the lubricant through the bearing equipped holes when the housing is detached from the bail, and a plate extending across the bearing equipped hole in the cover plate and connected removably to said cover plate.
